UNITED STATES PATENT OFFICE.

FRANK A. IDDINGS, OF WARREN, OHIO.

CHAIN-LINK DIE.

SPECIFICATION forming part of Letters Patent No. 319,724, dated June 9, 1885.

Application filed May 13, 1884. (No model.)

To all whom it may concern:

Be it known that I, FRANK A. IDDINGS, of Warren, in the county of Trumbull and State of Ohio, have invented certain new and useful 5 Improvements in Overlapping Chain-Link-Welding Dies; and I do hereby declare the following to be a full, clear, and exact description of the invention, such as will enable others skilled in the art to which it pertains to make 10 and use the same.

My invention relates to overlapping welding-dies, the object being to provide dies adapted to weld the links of chains, car-coupling links, or other similar work, and so arranged that each die, when it engages the work, overlaps or reaches beyond the surface of the work that is engaged by other dies of the machine, to the end that no fins or rough places are left on the work, but the welded 15 part when the work is finished is of equal size as other parts that have not engaged the dies. With these objects in view my invention consists in certain features of construction and in combination of parts, hereinafter described, 20 and pointed out in the claims. These dies are more especially adapted to be operated in a machine fully described in Patents No. 115,555, dated June 6, 1871, and No. 146,374, dated January 13, 1874, and a description of the machine is therefore not considered necessary in 25 this specification.

In the accompanying drawings, Figure 1 is a side elevation of one of the grasping-dies, with a finished link in position, and showing in vertical section a portion of the link previously welded and the vertical dies and plunger or end die in section. Fig. 2 is a side elevation of one of the grasping-dies, with a blank in position for welding, and in vertical section 30 a portion of the previously-welded link. Fig. 3 is a view in perspective of the grasping or holding die. Fig. 4 is a view in perspective of one of the vertical dies. Fig. 5 is a view in perspective of one of the side dies. Fig. 6 is 35 a front end elevation of the grasping-dies, with a portion of a finished link in position to receive the blank. Fig. 7 is an elevation of the five dies as would be seen from the front, with the grasping-dies removed and placed 40 as near together as their overlapping parts

will admit—a position, however, that they never assume in working. Fig. 8 is an elevation of the same, with the dies drawn back.

A and A' are the grasping or holding dies, that are opened and closed sidewise and are 55 provided with suitable corresponding grooves, a and a', into which the legs of the blank B are inserted, as shown in Fig. 2, and held firmly by the closing of the dies while the welding is done. The projecting rear end, A², 60 serves as a form over which the ends of the blank are bent, and may be of any desired shape, semicircular, as shown, or otherwise. If the wire of the blank is square or rectangular in cross-section, the groove a² is not re- 65

C are the vertical dies, that are reciprocated and strike the blank simultaneously from opposite directions. These dies are curved on their faces to correspond with the form A², and, in 70 case the wire of the blank is of round iron, are grooved, as shown at c. The groove extends somewhat more than a quarter of a circle in cross-section.

D is the end die, that takes the place of the 75 ordinary heading-die or plunger in forging, and is curved to correspond with the form A², and has a groove, d, corresponding with the groove c on the dies C.

E are the side dies, that are reciprocated 80 horizontally and strike the blank simultaneously on opposite sides. The sides of these dies at e are curved to fit the form A² nicely, and have a groove, e², on the edge, corresponding in form with the grooves c and d. The 85 parts c' of the dies C and the parts d' of the dies D overlap each other a considerable distance on the surface of the blank. The parts c' of the dies C and the parts d' of the dies D, as the dies successively strike the blank, overlap the strokes of each other; also, the edges e² of the dies E reach so far round that they engage a portion of the surface of the blank that has been engaged by the dies C and D, and by means of the overlapping of the dies 90 no ridges or fins are made; but the welded part when finished has a smooth surface and corresponds in size with the other parts of the link.

In operating the machine the blank B is 95

inserted in the grasping-dies, as shown in Fig. 2. The dies C first strike the protruding ends of the blank, bending them together around the form A², and are succeeded, preferably, by 5 the die D, followed by the dies E. The dies follow each other in quick succession, and it requires but a moment to complete the operation. The grasping-dies are next opened for removing the welded link, after which they 10 are partially closed before receiving the next blank. If the links are to form a chain, the welded link is hung in the recess I made in the front ends of the grasping-dies, and the lower leg of the blank is passed through the 15 last-formed link, as shown in Fig. 2, and the operation of welding is repeated. In case the wire of the blank is square or rectangular, the grooves in the dies and in the form A² are omitted, and the dies should be of sufficient 20 width to extend beyond the edges of the blank, so that these edges will be made full and square. If half-round iron is used, the groove in the form A² is omitted and those in the dies 25 retained.

25 In my Patent No. 304,526, granted September 2, 1884, I show and describe grasping and shaping dies arranged in pairs, each pair moving in planes at right angles to the other pair, and each die constructed to overlap or reach 30 beyond the lines where the adjacent dies en-

gage the blank, and an end die the face of which is constructed to overlap or reach beyond the line where the shaping-dies engaged the blank, and hence I make no broad claim to such construction in this application, but 35 confine myself more particularly to the peculiar construction of the several dies.

What I claim is—

1. The dies A A', constructed to grasp and hold the blank, and provided at their inner ends with the form A², substantially as set forth.
2. The combination, with grasping or holding dies having a projection for supporting a welded link in position for passing one end of 45 a blank through said link, of dies for welding and shaping the blank, substantially as set forth.
3. The combination, with grasping-dies arranged as aforesaid, of the overlapping welding-dies C C D and E E, arranged and operated as described.

In testimony whereof I sign this specification, in the presence of two witnesses, this 3d day of May, 1884.

FRANK A. IDDINGS.
